WINDOW SEAT

Filed June 4, 1928

Walter S. Lucas

INVENTOR

BY *Victor J. Evans*

ATTORNEY

UNITED STATES PATENT OFFICE

WALTER S. LUCAS, OF CHICAGO, ILLINOIS

WINDOW SEAT

Application filed June 4, 1928. Serial No. 282,766.

This invention relates to certain novel improvements in window seats, and has for its principal object the provision of an improved construction of this character which will be highly efficient in use, and economical in manufacture.

Among the several objects of the invention is to provide a seat construction which may be conveniently attached to a window construction to provide a seat on the outside thereof which seat may be used for the purpose of washing windows and the like.

A still further object of the invention is to provide a seat which seat may be adjusted to accommodate the opening of various window constructions.

Other objects will appear hereinafter.

The invention consists in the novel combination and arrangement of parts to be herein-after described and claimed.

The invention will best be understood by reference to the accompanying drawings, wherein a preferred form of construction is shown, and in which:

25 Fig. 1 is a perspective view of the seat embodying the invention showing the same applied to a window construction;

Fig. 2 is a fragmentary sectional detail view taken substantially on line 2-2 of Figure 1;

30 Fig. 3 is a fragmentary sectional detail view taken substantially on line 3-3 of Figure 2; and

Fig. 4 is a sectional detail view taken substantially on line 4-4 of Figure 1.

35 To accomplish the several objects of my invention, I provide a seat structure which includes two sections 10 and 11 adjustable longitudinally with respect to each other. Each section includes an end bar 12 providing

40 a horizontal arm 13 and vertical arm 14 to which the bars 15 are attached by means of bolts 16 or the like. The sections further include inner bars 17 likewise providing horizontal arms 18 and vertical arms 19 and secured to the bar 15 by means of bolts 20 whereby to provide sliding relation between the sections. The seat bars are indicated at 21 and are secured to the horizontal arms 13 and 18 by means of bolts 22.

45 The sides of the seat construction are indi-

cated at 23 and these sides are preferably formed from a length of material bent to provide a horizontal length 24 and side lengths 25 which incline toward each other and secured to the arms 13 by means of bolts 55 26. The sides are further secured to the arms 14 by means of bolts 27. Adjustably associated with the horizontal lengths 24 are arms 28 slidably arranged between spaced guiding ears 29 provided by the horizontal 60 lengths 24. These arms 28 have formed therein aligned openings 30 for the projection of a wing bearing nut 31 which is projected through an opening 32 formed in the horizontal lengths 24 whereby the arms 28 65 may be adjusted longitudinally of the lengths 24. The ends of the arms are bent substantially at right angles to provide heads 33 which are adapted to engage the side jambs 70 34 of the window construction 35.

The seat proper of the seat construction is further secured to the sill 36 of the window construction by means of arms 37. These arms 37 have their end portions 38 formed to provide hooks 39 which engage the edge 75 40 of the sill 36. The opposite end portion of these arms 37 are provided with elongated slots 38' through which projects the wing bearing nut 39 projected through an opening 40 formed in one of the bars 21, the arrangement being such that the arms 37 may be adjusted to have hooked engagement with the sill 36.

The sections 10 and 11 are latched in adjusted position by means of a latch structure which includes a plate 41 fixed to certain of the bars 15 by means of bolts 42. To this plate is hinged a latch 43 having an opening 44 adapted to selectively register with aligned openings 45 formed in one of the bars 21 and when the opening 44 is in alignment with one of the openings 45, there is adapted to be projected through the registering openings a lock pin (not shown).

It will be apparent from the description herein that the window construction may be adjusted to various lengths and width to be associated with window openings of various widths. It is intended that the material 100

used be of such thickness as to increase the lightness of the window seat construction.

By the use of a window seat construction herein set forth it is manifest that the window washer may conveniently be supported on the outside of a window for washing the window panes and the like.

While I have illustrated and described the preferred form of construction for carrying the invention into effect without departing from the purview of the invention. I, therefore, do not wish to be limited to the precise details of construction herein set forth, but desire to avail myself of such variations and modifications which would come within the scope of the appended claims.

Having thus described the invention, what I claim as new and desire to protect by Letters Patent, is:

20. 1. A window seat including two sections adjustable relatively to each other, means adapted to engage the side jambs of a window construction for supporting said sections from said jambs, and adjustable means for 25 connecting said sections to the sill of said window construction, said adjustable means including spaced members having end portions bent to provide hooks for hooked engagement with the edge of the sill and provided with elongated slots, and bolt members projected through said slot and portions of 30 said sections for connecting said members to said sections in a predetermined adjusted position.

35. 2. A window seat including two sections adjustable relatively to each other, means adapted to engage the side jambs of a window construction for supporting said sections from said jambs, and adjustable means for 40 connecting said sections to the sill of said window construction, said adjustable means including spaced members having end portions bent to provide hooks for hooked engagement with the edge of the sill and provided with elongated slots, and bolt members projected through said slot and portions of 45 said sections for connecting said members to said sections in a predetermined adjusted position, and means for releasably latching 50 said sections in a predetermined adjusted position.

3. In a device of the character stated, substantially L-shaped supporting members, rails extended between said supporting members in spaced apart relation, the rails extending between certain of said supporting members being disposed to extend between the rails extended between other of said supporting members whereby two interfitted frame members will be defined, a hingedly mounted member secured to certain of said rails, and means engageable by a portion of 55 said hingedly mounted member for holding said frames against movement relative to 60 each other.

4. In a device of the character stated, substantially L-shaped supporting members, rails extended between said supporting members in spaced apart relation, the rails extending between certain of said supporting members being disposed to extend between the rails extended between other of said supporting members whereby two interfitted frame members will be defined, a hingedly mounted member secured to certain of said rails, means engageable by a portion of said hingedly mounted member for holding said frames against movement relative to each other, arm members extending outwardly from said L-shaped supporting members disposed at the outer ends of said frames, members adjustably attached to said arm members adapted to engage the jambs of a window construction to connect said frame members thereto, and means for adjustably connecting said frame members to the sill of said window construction.

In testimony whereof I affix my signature.

WALTER S. LUCAS.
